US0D1022142S

(12) **United States Design Patent** (10) Patent No.: **US D1,022,142 S**
(45) Date of Patent: ** Apr. 9, 2024

(54) **WALL-MOUNTED MIXING FAUCET**

(71) Applicant: **Greatness Sanitary Industrial Co., Ltd.**, Xiushui Township, Changhua County (TW)

(72) Inventor: **Wei-cheng Chung**, Xiushui Township (TW)

(73) Assignee: **Greatness Sanitary Industrial Co., Ltd.**, Xiushui Township (TW)

(**) Term: **15 Years**

(21) Appl. No.: **29/766,816**

(22) Filed: **Jan. 19, 2021**

(51) LOC (14) Cl. **23-01**

(52) U.S. Cl.

USPC **D23/241**

(58) **Field of Classification Search**

(57) **CLAIM**

The ornamental design for a wall-mounted mixing faucet, as shown and described.

DESCRIPTION

FIG. 1 is a perspective view of a wall-mounted mixing faucet showing my new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines in the figures show portions of the wall-mounted mixing faucet that form no part of the claimed design.

1 Claim, 7 Drawing Sheets
